MAX KATZ INVENTOR.

BY Thomas A. Jenkins, Jr.
ATTORNEYS.

UNITED STATES PATENT OFFICE.

MAX KATZ, OF PROVIDENCE, RHODE ISLAND.

FOUNTAIN PEN.

Application filed February 15, 1926. Serial No. 88,352.

My invention relates to fountain pens.

The main object of my invention is to provide a nonleakable fountain pen provided with means to furnish the desired amount of ink to the writing end thereof.

The problem of feeding the desired amount of ink to the pen nib in fountain pens has always existed since the beginning of fountain pen manufacture. At first it was apparently thought that it was necessary to force the ink to the pen nib by compression of the ink sack in some manner to secure a proper flow of ink, and practically all of the earlier patents show some means for forcing the ink down to secure a proper flow thereof while writing. Then it was apparently discovered that although the atmospheric pressure would retain the ink in the sack under ordinary conditions that once the flow of ink was started that the capillary action of the ink flowing downwards on to the sheet of paper would cause sufficient ink to be withdrawn from the ink sack for writing purposes, provided however, that means were provided in the pen for letting in an amount of air to balance the volume in the sack to compensate for the volume of ink withdrawn. Since then whether the manufacturer has known it or not fountain pens have been provided with some means to permit an equal influx of air to the ink sack. This has been accomplished in various manners, such as by providing a layer of absorbant material underneath the pen nib, by providing a large ink and air groove on the front surface of the feed portion or in any other manner so loosely joining the feed portion and neck portion together or the pen nib to the pen or the neck portion to the barrel or otherwise that sufficient air may go into the ink sack to permit the pen to write. The disadvantage of all prior constructions however, so far as the applicant is aware, has been that the air inlet openings have been too large or the joints have to be so loose that so much air has been introduced through so many places that the atmospheric balance has been disturbed and that the pen will leak. By providing an internal channel in the feed portion leading from the ink sack to approximately the lower end thereof and by providing two openings leading from the front surface of the feed portion to said channel of smaller diameter than said channel and of approximately equal diameter, one

an air inlet opening substantially in register with the air inlet opening in the pen nib and the other an ink outlet opening substantially in register with the usual split in the pen nib below said air inlet opening, I permit the desired quantity of ink to be forced by the capillary action produced in writing through said ink outlet opening and an exact equal balancing amount of air to be introduced into said ink sack through said air inlet opening.

Having provided means to admit the necessary amount of air to the ink sack to compensate for the volume of ink withdrawn in writing and it being no longer necessary to have loose joints to admit other air to said ink sack, it is obvious that the rest of the pen may be constructed in a nonleakable manner. To this end I preferably integrally secure the neck portion to the barrel portion to eliminate the leakage formerly caused at this point, and the unsteadiness in writing caused by the joint between said portions becoming loose in use. The pen nib may be attached as usual between the feed portion and the inner periphery of the neck portion and I preferably construct the inner periphery of the neck portion of a substantially equal diameter to that of the outer periphery of the feed portion so that there will be no leakage at this point. As the feed portion is provided with a substantially central channel it is obvious that there will be no ink loss around either joint for the channel discharges much below them below the centre of the pen nib. Hitherto for some reason the neck portion has been constructed separately from said barrel portion and has been provided with an internal shoulder to receive the lower end of the feed sack. It is obvious by providing the internal shoulder for the lower end of the feed sack on the upper end of the feed portion and by constructing the preferably curvilinear neck portion integral with the barrel portion that I have eliminated many steps formerly thought necessary in the manufacture of fountain pens and have almost cut the cost of their manufacture in half by moulding the barrel and neck portion integrally together, particularly where fountain pens are constructed of celluloid or similar material.

These and such other objects of my invention as may hereinafter appear will be best understood from a description of an embodi-

ment thereof such as is shown in the accompanying drawings.

In the drawings, Fig. 1 is a side elevation of an assembled fountain pen constructed in accordance with my invention having the cap removed.

Fig. 2 is a longitudinal sectional view of the writing end thereof held in writing position.

10 Fig. 3 is a disassembled side elevation of the feed portion and pen nib illustrating the location of the openings on the lower end of the feed portion.

Fig. 4 is a plan view of the feed portion.

15 Fig. 5 is a side elevation of the feed portion.

Fig. 6 is a reverse plan view of the feed portion.

20 Fig. 7 is a plan view of the lower writing end of the fountain pen.

Fig. 8 is a side elevation of the lower writing end of the fountain pen.

25 Fig. 9 is a reverse plan view of the lower writing end of the fountain pen.

30 In the drawings, wherein like characters of reference indicate like parts throughout, 10 generally indicates a fountain pen constructed in accordance with my invention. In the description and claims I refer to the

35 position the fountain pen takes in use, the word "upper" referring to the closed end and the word "lower" referring to the writing end, the word "front" referring to the pen nib side and the word "back" referring to the opposite side therefrom. The preferred embodiment of nonleakable fountain pen shown contains the usual tubular barrel sack holding portion 12 preferably provided with a closed upper end 14 and an open

40 lower end 16. The outer periphery of the barrel 12 is preferably constructed of varying diameters to conform to the usual configuration. Said pen also contains the usual neck portion 18 which preferably terminates in the usual outwardly flaring annular flange

45 20. On a suitable position on the outer periphery of the neck portion 18, I also preferably provide the cap receiving thread 22.

50 Though the neck portion 18 may be constructed separately from the barrel portion 12, I preferably integrally secure the hollow upper end 24 of the neck portion to the open lower end 16 of the barrel portion 12 in any suitable manner. Though the neck

55 portion is preferably of the usual curvilinear shape due also to its varying diameter, it is obvious that it may throughout its length be of an approximately equal diameter or may be of any other suitable configuration.

60 A pen nib 26 of usual configuration is preferably attached to the lower end of said pen 10. The pen 10 also contains the usual ink sack 28 provided with the usual open lower end 30 to feed ink from said ink sack

65 28 to said pen nib 26. To provide means to

suitably secure the pen nib 26 to said pen 10, I preferably provide the usual feed portion 32. Said feed portion 32 is of the general usual configuration, but differs from former feed portions in the following particulars. The upper end 34 thereof is provided with the sack receiving shoulder 36 of smaller diameter than the rest of the feed portion so that the lower open end 30 of said feed sack 28 may be attached thereto. 75 The central portion 38 is made if anything of a larger diameter than usual approximating the diameter of the inner periphery 40 of the neck portion 18. In place of the usual central groove on the front surface 50 of said feed portion 32 to provide an ink duct from said ink sack 28 to said pen nib 26, I preferably provide said feed portion 32 with a nonleakable ink duct 42, said ink duct 42 comprising an internal channel extending from the upper sack end 34 of said feed portion 32 to approximately the lower end 45 of said feed portion and discharging underneath the lower portion of the pen nib 26. As explained, a main feature of my invention is to provide two openings in the duct 42 leading from the ink sack to the pen nib 26. The pen nib 26 is provided with the usual writing end 44 having the usual split 46 therein extending upwards to the usual air inlet opening 48 located approximately centrally thereof.

To assemble the pen it is obvious that the lower end 30 of said ink sack 28 is first expanded to fit around the sack receiving shoulder 36 on the upper end of the feed portion, the pen nib 26 is then laid on top of the front surface 50 of the feed portion and the feed portion with attached sack 28 forced inwardly of the neck portion 18 and the barrel 12. It is obvious that as the feed portion is approximately equal in diameter with the inner periphery of the neck portion that the upper end 52 of the pen nib 26 is thereby compactly secured to the fountain pen between the outer periphery 38 of the feed portion 32 and the inner periphery 40 of the neck portion 18. As usual I also preferably cut away as at 54 the lower rear end of the feed portion to make it conform to the usual configuration of said portion.

As stated, I preferably provide means to admit a sufficient quantity only of air to the ink sack 28 while writing. To this end I preferably construct two openings 60 and 62 of substantially smaller diameter than the ink duct 42 and preferably of a substantially equal size extending from the front surface 50 of said feed portion 52 to the lower end of said channel 42, one being an air inlet opening 60 which when the pen nib 26 is inserted and the pen properly assembled as hitherto explained will be substantially in register with the usual air inlet opening 48 on the pen nib and the other an

ink discharge opening 62 located below said air inlet opening 60 and preferably substantially in register with the split 46 in the lower end of the pen nib 26 below the air inlet opening 48. The pen 10 may also be provided with a suitable usual lever 64 adapted to compress the plate 66 to exhaust all the air and other matter out of the sack 28 and to cause a vacuum therein prior to dipping the lower writing end of said pen nib 26 into an ink well so that the atmospheric pressure may cause the ink to flow into the vacuum formed in the ink sack 28 on release of said plate to fill said ink sack 28 with ink.

The operation and functioning of my invention is obvious from the above description. When the pen is held in writing position and as shown in Fig. 2 used for writing, it is obvious that once the flow of ink has started due to the scratching of the pen point on the paper 70, that the capillary action of the already laid ink 72 on said paper will draw the ink 74 from the ink sack 28 through the ink duct 42 through the ink discharge opening 62 and down the split 46 in the pen nib to the pen point 47, and on to the paper 70. In order for the supply of ink 74 to continue evenly, I have provided the air inlet opening 60 of an approximately equal size for this purpose. It is thus obvious that as ink flows downwards as just explained that an equal amount of air 76 to compensate for the ink removed will be introduced to said sack 28 through the usual air inlet opening 48 in the pen nib 26 through the air inlet opening 60 in the feed portion 32 and up the ink duct 42 in the form of the bubbles 76 as shown in Fig. 2 (probably grossly exaggerated to show the action) and into the air space 77 then formed in the ink sack 28 above the level of the ink 75 therein. As this construction permits the exact amount of ink needed for writing purposes to be withdrawn from the ink sack 28 and a balancing amount of air introduced therein, the parts of the pen being of such a size that the balancing effect is produced without leakage, it is also obvious that I have so constructed my pen that influx of air at the other points is no longer needed, and that it is therefore leak proof. As the ink duct 42 discharges much below the point of securement of the upper end 52 of the pen 10 between the outer periphery of the feed portion 32 and inner periphery of the neck portion 18 it is obvious that there can be no leakage at this point. As the pen nib 26 is firmly secured to the front surface of the feed portion, it is obvious that there can be no leakage at this point. As the neck portion 18 is preferably constructed integral with the barrel 12 it is obvious that there can be no leakage at this point. It is thus obvious that I have provided a practi-

cally nonleakable fountain pen provided with suitable means to feed ink in desired amounts for writing purposes.

It is understood that my invention is not limited to the specific embodiment shown and that various deviations may be made therefrom without departing from the spirit and scope of the appended claims.

What I claim as new and desire to secure by Letters Patent is:

1. A nonleakable fountain pen, comprising, an ink sack holding barrel portion having a closed upper end and an open lower end, a hollow neck portion having a cap receiving thread on the outer periphery thereof integrally secured to the barrel portion, a tubular feed portion having its central portion of approximately the diameter of the inner periphery of the neck portion, an ink sack receiving shoulder of smaller diameter at the upper end and an internal channel extending from the upper sack end thereof to approximately the lower end thereof having an air inlet opening of substantially smaller diameter than the channel extending from the front surface of said feed portion to said channel and an ink outlet opening of substantially equal size extending from the front surface of said feed portion to said channel below said air inlet opening, an ink sack having a lower open end attached to the shoulder on the upper end of said feed portion and a pen nib having the upper end thereof secured to said pen between said neck portion and said central portion of said feed portion, a downwardly projecting split writing end and an air inlet opening approximately centrally thereof substantially in register with the said air inlet opening in the feed portion.

2. A nonleakable fountain pen, comprising an ink sack holding barrel portion having a closed upper end and an open lower end, a hollow neck portion secured to the barrel portion, a tubular feed portion having an ink sack receiving shoulder at the upper end and an internal channel extending from the upper sack end thereof to approximately the lower end thereof having an air inlet opening of substantially smaller diameter than the channel extending from the front surface of said feed portion to said channel and an ink outlet opening of substantially equal size extending from the front surface of said feed portion to said channel below said air inlet opening, an ink sack having a lower open end thereof attached to the shoulder on the upper end of said feed portion and a pen nib having the upper end thereof secured to said pen, a downwardly projecting split writing end and an air inlet opening approximately centrally thereof in register with said air inlet opening in the feed portion.

3. A fountain pen having an ink sack

contained therein, a split pen nib secured to the lower end thereof having an air inlet opening therein, an internal channel connected to said ink sack and discharging underneath said pen nib in two substantially equal relatively small openings, one an air inlet opening substantially in register with

the air inlet opening in the pen nib and the other an ink outlet opening substantially in register with the split in the pen nib below 10 said air inlet opening.

In testimony whereof I affix my signature.

MAX KATZ.
